UNITED STATES PATENT OFFICE.

THOMAS GEORGE STILES, OF ARLINGTON, NEW JERSEY.

SWITCH LOCK MECHANISM.

Application filed July 2, 1921. Serial No. 432,054.

To all whom it may concern:

Be it known that I, THOMAS GEORGE STILES, a citizen of the United States, and resident of Arlington, in the county of Hudson and State of New Jersey, have invented certain new and useful Improvements in Switch Lock Mechanism, of which the following is a specification.

This invention relates to switch mechanism and particularly to improvements in switch mechanism of the type forming the subject of Letters Patent No. 1,253,439 granted to me January 15, 1918.

The switch mechanism of my aforesaid patent comprises a front rod connecting the switch rails, a lock rod operatively connected with said front rod for movement therewith in the shifting of the rails, a locking plunger movable transversely to said lock rod and cooperative with notches therein positioned to effect locking of the switch rails in their respective switching positions, and a guide or casing supporting the lock rod and locking plunger at their locking point and maintaining them in operative relation.

In this switch mechanism, as in others of like character, there is no means to limit the interlocking movements of the locking plunger, so that it sometimes happens that the plunger becomes withdrawn from its guide or casing, as, for instance, in the event of its being caught by a brake beam or other part hanging from a car passing over the rails.

Because of this liability of the locking plunger becoming withdrawn from its supporting guide or casing, and a consequent interference with the normal operation of the switch locking mechanism, it has been the object of my invention to provide a simple and efficient means for defining the unlocking movement of the plunger and maintaining it in operative relation to the lock rod. This object I attain by the novel construction and combination of parts as illustrated in the accompanying drawings forming part of this specification, in which—

Fig. 1 is a plan of a switch mechanism embodying my present invention;

Fig. 2 a vertical transverse section of the same, the section being taken on the line 2—2 of Fig. 1.

Fig. 3 an enlarged plan of the switch lock mechanism;

Fig. 4 an end elevation of the same, look-

ing from the right in Fig. 2, with the lock rod removed;

Fig. 5 a vertical section through the longitudinal center of the same, showing the locking plunger withdrawn to its unlocking position; and

Fig. 6 a bottom view of the locking plunger removed from connection with its cooperating mechanism.

Similar reference characters indicate like parts in the several figures of the drawings.

Referring first to Fig. 1, the reference numerals 3—3 designate a pair of stock rails, and 4—4 a pair of point-rails of a switch, the stock rails being supported on suitable ties 5, and braced by suitable rail-braces, such as 6.

The points of the switch rails may be connected in any usual or suitable manner, the same as here shown being connected by a front rod *f* of the type shown in my aforesaid patent, said rod being secured at its ends to the opposite switch rails by suitable fastening means, such as the bolts and nuts 11 and 12.

Connected with this front rod by a suitable coupling 17 is a lock rod 22, which latter at its outer or locking end is slidably mounted in substantially usual manner on a suitable base 36, this base in turn being supported on a plate 37 secured to the ties 5.

The outer end of the lock rod 22 is preferably flat or oblong in cross-section and has relatively long locking notches 31, the length of which may be varied by a suitable adjusting bar 32, the position of which may be determined at one end by a bolt and nut 33 and 34, and at the other end by suitable fastening and check nuts, designated generally by 35. The manner in which this adjustment is obtained will be clear by reference to Figs. 1, 2 and 3. Into the notches 31 so formed is adapted to pass a locking plunger *p*, which is mounted on the base 36 in substantially usual manner, a cover 38 being bolted to the base and forming therewith a casing in which the lock rod and its locking plunger are supported for movement in directions transverse to each other as shown.

With this construction, when the plunger is drawn backwardly to a position to release the lock rod, that is, to a position withdrawn from one of the notches 31 in said rod, the latter is free to permit of a shifting or adjusting of the switch points.

After the switch points have been adjusted, the plunger is then returned to locking position within one of the locking notches in the lock rod.

- 5 The construction and operation of the parts as thus far described is the same as that of the similar parts in my aforesaid patent, to which reference may be had. In accordance with my present invention, as 10 herein referred to, means are provided for limiting the movements of the plunger on its base and thereby maintaining it in operative relation to the lock rod. A simple and efficient means for doing this comprises 15 a fixed stud 40 on the base 36 (see Fig. 5) engaging stop surfaces 41 and 42 on the plunger, the arrangement of said stop surfaces being such as to permit of the plunger being withdrawn a short distance from lock- 20 ing engagement with the lock rod, as shown in Fig. 5, and a return movement of the plunger to locking position within one of the notches in the lock rod, as shown by dotted lines in Figs. 3 and 4.
- 25 The stop surfaces 41 and 42 on the plunger lock may be provided in any suitable way. Preferably and as here shown they are provided by forming a longitudinal groove 43 in the under side of the plunger, into which 30 the stop stud 40 extends, and the end walls of which provide the said stop surfaces with which the stud 40 engages.

The top of the casing formed by the parts 36 and 38 is provided with an inspection 35 opening 50 which may be closed by a hinged cover 51. When the cover is thrown back it will be easy to see at a glance just what the condition of the lock is at the locking 40 point and any undue wear that has taken place may be readily detected and suitable adjustment of the parts made.

What I claim is:—

1. In a switch mechanism, the combination with a pair of switch rails, of switch 45 locking means comprising a stationary supporting base located laterally beyond one side of said rails, a lock rod operatively connected at one end with said rails and at its opposite end slidably mounted on said 50 base and provided with locking means, a locking plunger slidably mounted on the base for longitudinal movement to and from

a position cooperative with the locking means of the lock rod, and means limiting the longitudinal movement of the locking 55 plunger relatively to the lock rod.

2. In a switch mechanism, the combination with a pair of switch rails, of switch locking means comprising a stationary supporting base located laterally beyond one 60 side of said rails, a lock rod operatively connected at one end with said rails and at its opposite end slidably mounted on said base and provided with locking means, a locking plunger slidably mounted on the 65 base for longitudinal movement to and from a position cooperative with the locking means of the lock rod, said locking plunger being provided with a stop surface, and means on the base for engaging said stop 70 surface on the locking plunger to limit the longitudinal movement of the latter relatively to the lock rod.

3. In a switch mechanism, the combination with a pair of switch rails, of switch 75 locking means comprising a lock rod operatively connected with said rails, a locking plunger movable transversely to and cooperative with said lock rod at the locking point, said locking plunger being provided with a longitudinal groove having end walls, and a fixed stud entering said groove in the 80 locking plunger and engaging the end walls thereof to limit the movement of the plunger relatively to the lock rod.

4. In a switch mechanism, the combination with a pair of switch rails, of switch locking means comprising a lock rod operatively connected with said rails for movement therewith, a locking plunger movable 90 transversely to and cooperative with said lock rod at the locking point, said locking plunger being provided with a pair of stop surfaces, and a base plate having said 95 plunger slidably mounted thereon and provided with a fixed stud for engaging the stop surfaces on the plunger to limit the movement of the latter relatively to the lock rod.

Signed at New York, in the county of 100 New York, and State of New York, this 29th day of June A. D. 1921.

THOMAS GEORGE STILES.
